UNITED STATES PATENT OFFICE.

CHARLES H. TRIPHAGEN, OF PEWAMO, MICHIGAN.

VEHICLE-WHEEL.

SPECIFICATION forming part of Letters Patent No. 234,506, dated November 16, 1880.

Application filed October 8, 1880. (Model.)

To all whom it may concern:

Be it known that I, CHARLES H. TRIPHAGEN, of Pewamo, in the county of Ionia and State of Michigan, have invented an Improvement in Carriage-Wheels, of which the following is a specification.

The nature of my invention relates to certain new and useful improvements in the construction of carriage-wheels; and the invention consists in the peculiar construction and arrangement of the parts by means of which a wheel of great lightness, durability, and strength is obtained, as hereinafter more fully described.

15 In the drawings, Figure 1 is a vertical longitudinal section through the center of the hub, with the spokes shown in dotted lines. Fig. 2 is a vertical cross-section on the line *x x*, Fig. 1.

20 In the accompanying drawings, which form a part of this specification, *A A'* represent two parts of the hub, made of cast metal, hollow or like cups, the outer ends thereof being open, while their inner ends, *a a'*, are solid, with a 25 central perforation in each, and with the inner faces of each provided with a circumferential projection, *b*. The central perforations are threaded, as shown, to engage with corresponding right and left hand threads upon each end 30 of a metallic cylinder, *B*, by means of which the two parts of the hub *A A'* are secured together, leaving a space between the two ends *a a'* to receive the spokes *C*, the sides of which are notched to engage with the projections *b*, 35 while their inner ends rest upon the circumference of the cylinder *B*.

D is a sand-band, made of cast metal, hollow, its outer end being open, its inner end being solid, as shown, with a central perforation, threaded to engage with a similar thread 40 upon the inner end of the pipe-box *E*, which passes forward through the parts *A A'* and cylinder *B*, when its forward end, being threaded, passes through a central perforation, correspondingly threaded, in the hollow metallic 45 band *F*, which forms the outer end of the hub.

The outer ends of the parts *A A'* are interiorly-threaded, as shown, to engage with corresponding threads upon the exterior of the inner ends of the bands *D F*, or, if preferred, 50 these bands may be cast with flanges projecting inward, and such flanges may be interiorly-threaded to engage with exterior threads upon the outer ends of the parts *A A'*.

By this means of construction a strong, light, 55 and durable wheel is obtained, the parts being easily removed for necessary repairs and for the insertion of new spokes when required.

What I claim as my invention is—

The vehicle-hub described, consisting of the 60 hollow metallic shells *A A'*, having the flanges *b*, the short cylinder *B*, by which such metallic shells are kept in place, the sand-bands *D F*, screwed to the metallic shells *A A'*, and the pipe-box *E*, secured to the said bands *D F*, all 65 constructed and arranged substantially as described and shown.

CHARLES H. TRIPHAGEN.
